GALVANIZING APPARATUS

Filed June 9, 1944

UNITED STATES PATENT OFFICE

2,424,808

GALVANIZING APPARATUS

Meril L. Eckman, Canton, Ohio, assignor to Republic Steel Corporation, Cleveland, Ohio, a corporation of New Jersey

Application June 9, 1944, Serial No. 539,407

1 Claim. (Cl. 91—12.5)

1
This invention relates generally to apparatus for handling elongated cylindrical metal articles and more particularly to new and improved means for spreading liquid substantially uniformly on surfaces of magnetic metal tubular articles and removing excess liquid therefrom.

Galvanized tubes have been removed from galvanizing tanks heretofore in various manners, for example, by being lifted straight up and also by being pulled endwise, in each instance one end of the pipe being kept higher than the other end to enable the excess molten metal to flow out of the tube and back into the tank. The thickness of coating metal on galvanized tubes so removed from the tank is not uniform circumferentially of the tube and more metal than is necessary or desirable remains in the tube, particularly if the tubes are spirally corrugated, as is quite common.

The present invention makes it possible to overcome these prior shortcomings and to make tubular articles which have galvanized coatings substantially uniform in thickness over all the surfaces of the article. These advantages are important commercially, especially in the galvanizing of tubular articles which are corrugated. This invention may also be used to good advantage on tubular articles or cylinders which have a liquid on surfaces thereof, including paint, pickling liquor and molten metals, and is generally useful in handling elongated cylindrical magnetic metal articles, whether coated with liquid or not.

In the drawings accompanying and forming a part of this specification,

Figure 1 is a side elevational view of a galvanizing tank equipped with apparatus embodying one form of the present invention;

Figure 2 is a top plan view of the apparatus of Fig. 1; and,

Figure 3 is a fragmentary and elevational view showing details of one of the magnetic rollers and associated parts.

In the figures, 1 designates a conventional tank in which galvanizing metal may be maintained in a molten condition and in which pipe or tubing A may be submerged. A conventional air ring 2 is located at one end of the tank 1. This ring has a large enough inside diameter for the articles A being galvanized to pass axially therethru. The ring is hollow, is connected to a source of air under pressure (not shown), and is provided with a plurality of openings circumferentially spaced therearound so that air may be discharged from the ring against substantially the entire outer surface of a tube A as it passes thru the ring.

A supporting frame 3 located at the discharge end of tank 1 supports cross bars 4 from which a plurality of rollers 5 are suspended. These rollers are of the magnetic type, that is, they are ca-

5 pable of attracting a magnetic metal article to and holding it against their surfaces. This attracting force may be furnished by magnets within the rollers or preferably by passing current thru windings in the rollers. These rollers 5 have concave article engaging surfaces 6 which, preferably, are in the form of truncated cones with the small ends of the cones adjoining each other, but which, obviously, may be of various shapes, even to the extent of being roughly semi-circular. Each roller 5 is carried by a housing 7 which has a shaft-like extension 8 rotatably secured in a bearing block 9 carried by a bar 4 of frame 3. The extension 8 may be adjusted in block 9 to position the axis of the roll 5 at the desired various acute angles to the longitudinal axis of a tube being withdrawn from tank 1 thru ring 2. An indicator 10 at the upper end of extension 8 shows the angularity of the roll to the center line of the tube.

10 Each housing 7 carries a roller 5 and its actuating means. In the illustrated modification of the invention the roller 5 is of the type which is made magnetic by the flow of current thru windings (not shown) in the roller. That roller 5 is secured to a shaft 11 which is rotatably mounted in bearings in housing 7 and which is rotated by a gear 12 at one end meshing with another gear 13 on the rotor shaft of a motor 14 attached to housing 7. The terminals of the windings within the roller are connected to slip rings 15 which are secured to, but insulated from, block 16 on shaft 11 and make sliding contact with terminals 17 of a suitable source of electrical current.

15 The cross bars 4 are at successively higher elevations and, consequently, the rollers 5 define part of an upwardly inclined path of travel for the articles being moved thereby.

When a galvanized tube A is to be withdrawn 20 from tank 1, one end is raised and placed in ring 2 and the tube is then moved thru ring 2 until it is in contact with the first of the rolls 5, whereupon it is magnetically attracted to and held against that roller. As the first roller revolves about its axis, it propels the tube axially until it is similarly attracted to and held against the next roll 5, and this operation proceeds until all the rolls 5 are propelling the tube and, incidentally, continues until the tube leaves the last roll 5. While 25 the rollers 5 are propelling the tube or pipe endwise, as just described, the rollers also rotate the tube or pipe due to the angularity of the longitudinal axis of the rolls with respect to the longitudinal axis of the tube or pipe. As the tubular article moves upwardly on an incline due to the disposition of rolls 5 in an inclined plane, the molten metal on the article flows downwardly toward the tank 1. By varying the angularity of the rolls to the article the rate of rotation of the 30 article as well as the rate of longitudinal travel

of the article may be varied. As the article rotates the molten metal flows circumferentially on the article, thereby spreading out on the surfaces of the article. When the air blast from ring 2 is used, little excess molten metal remains on the outer surface, but any such metal on that surface and the excess molten metal on the inner surface will be spread over those surfaces quite uniformly by the motions of the article. The excess metal runs freely lengthwise and circumferentially of the article and drains into the tank, thereby providing a substantially uniform coating of the galvanizing metal on the surface of the article and returning most of, if not all, the excess metal to the galvanizing tank. When the article is corrugated either circumferentially or spirally the excess metal which otherwise would remain in the depressions flows, due to rotation of the article, over the crests of the corrugations or spirally and thus progressively flows lengthwise of the article toward the tank, without leaving considerable quantities of excess metal in the depressions.

The speed of rotation of rollers 5 may be varied within wide ranges, preferably by using variable speed motors but also, if desired, by substituting for gears 12 and 13 other gears having different gear ratios. The angularity of the longitudinal axis of roll 5 to the longitudinal axis of the tube may also be varied within wide limits by adjustment of extension 8. Since the speed of rotation of rollers 5 and the angularity of these rollers to the tube engaging them affect not only the speed of rotation of the tube but also its speed of longitudinal travel, it will be apparent that a wide variety of rotational speeds and longitudinal speeds of the tube may be obtained, and that these conditions may be varied to accomplish any one of a number of desired results. If, for example, the desire is to retain most of the molten metal in the tube, but to spread it more or less uniformly on the inner surface of the tube, the rotation of the tube may be at such a speed that the tendency of the molten metal to run lengthwise of the tube will be substantially overcome and yet its tendency to flow circumferentially on the inner surface of the tube will be permitted. In this instance the speed of lengthwise movement of the tube might be rapid or slow, depending on the amount of molten metal in the tube and the rate at which it cools to a non-flowing temperature. If it is desired that most of the molten metal in the tube should flow out of the tube, the speed of rotation of the tube may be slow enough to permit of such flow while some circumferential flow is caused. In this case the lengthwise movement of the tube would be relatively slow.

This and many other desired conditions may be readily obtained by simply varying the speed and angularity of the rolls. It will, therefore, be understood that the roll angularity and the gear ratios indicated on the drawings are merely representative of one set of conditions and that other

conditions may be obtained by the simple adjustments above described. It will also be understood that the present invention is not limited to tubes containing molten metal or any other liquid, but that it may be employed in the handling of tubes of magnetic material which are to be simultaneously rotated and propelled endwise.

It will be understood that the rollers 5 need not be arranged to move the article along an upwardly inclined path, altho that is preferable when the liquid removed from the article is to be returned to the tank from which the article was removed. When it is not important to collect the liquid in such a tank the rollers may be positioned to move the article along a downwardly inclined path. When the article has no liquid on it or removal of excess liquid from it is not especially desired, the rollers 5 may be positioned to move the article along a horizontal path. The rollers 20 may be located beneath the article if desired but preferably when the article carries any liquid which should be kept away from the bearings or supports of the rollers.

Having thus described my invention so that others skilled in the art may be able to understand and practice the same, I state that what I desire to secure by Letters Patent is defined in what is claimed.

What is claimed is:

30 In galvanizing apparatus including a tank for molten galvanizing metal and a ring to discharge gas under pressure against the outer surface of a tubular magnetic article as it is moved endwise therethrough from the tank, the combination of 35 a frame adjacent to said tank, roll housings, magnetic rollers, each housing carrying one of said rollers and the rollers being disposed in an inclined plane extending upwardly from said ring, said rollers being positioned to engage with the 40 upper surface of said article and energized to attract said article thereto, adjustable means suspending said housings from said frame and positioning the longitudinal axes of said rollers at acute angles to the longitudinal axis of the article, and separate motors carried by each of said 45 housings, each motor being operatively connected to the roller of its housing to rotate said roller.
